United States Patent Office.

GILBERT K. DEARBORN, OF PAWTUCKET, ASSIGNOR TO TIMOTHY EARLE,
OF SMITHFIELD, RHODE ISLAND.

Letters Patent No. 101,235, dated March 29, 1870.

IMPROVED KNIFE-GUARD.

The Schedule referred to in these Letters Patent and making part of the same.

I, GILBERT K. DEARBORN, of Pawtucket, in the county of Providence and State of Rhode Island, have invented certain Improvements in Adjustable Knife-Guards, of which the following is a specification.

The nature of my invention consists in the combination and arrangement of parts, as hereinafter more fully described.

Figure 1 is a side elevation of my invention.

Figure 2 is an elevation, showing the knife-guard turned to its extreme distance from the edge of the knife.

A is the handle of the knife.

B is the blade, upon which is placed the clasp F.

Between said blade B and handle A is placed the plate E, on which is the corrugated edge of a flange, D.

The clasp F and plate E, having holes made in them to receive the ends *a a* of the guard C, will thus become hinges, upon which said guard turns when being adjusted.

The corrugated edge-flange D or its equivalent, with the spring made in the guard C, will retain said guard in the desired position when being used.

The guard C is adjusted by pressing it from and toward the edge of the knife with the thumb of the hand which holds said knife.

When any defective part of the fruit is to be cut out, the guard C is turned to its extreme distance from the edge of said knife, thus permitting a free use of the blade B.

When said knife requires sharpening, the clasp F is taken from said blade, which will permit the end *a* of guard C nearest the handle to be disconnected, thus leaving the knife free of its guard and clasp.

What I claim as my improvement is—

In combination with the knife A B, the clasp F, provided with the corrugated flange D, the plate E, and hinged knife-guard C, all constructed as herein described, for the purpose specified.

GILBERT K. DEARBORN.
